UNITED STATES PATENT OFFICE.

HENRY ANGUS NICHOLSON, OF AUCKLAND, NEW ZEALAND,

CONSTRUCTION OF SHIPS' HULLS.

1,402,530.

Specification of Letters Patent.

Patented Jan. 3, 1922.

Application filed November 19, 1918, Serial No. 263,154. Renewed July 5, 1919. Serial No. 308,832.

To all whom it may concern:

Be it known that I, HENRY ANGUS NICHOLSON, subject of the King of Great Britain, residing at 95 Queen Street, Auckland, in 5 the Dominion of New Zealand, have invented new and useful Improvements in the Construction of Ships' Hulls; and I do hereby declare the following to be a full, clear, and exact description of the same.

10 This invention has been devised for the purpose of providing an improved method of constructing ships' hulls by the adoption of which important advantages are obtained both in the cost of construction and in the 15 general working of the ships after construction.

Hitherto it has been customary in the construction of ships' hulls, for the frames to be formed of varying contours from the bow 20 to the stern in order to obtain the vertical and longitudinal sweeps of the ships' sides and also the pitch of their bottoms. This necessitates the employment of highly skilled labour in the designing of the ship 25 and also the employment of highly skilled workers in the carrying out of the design.

With the adoption of the present invention the necessity for the employment of highly skilled labour in the designing of the 30 vessel is obviated by the employment of a method of construction under which the designs of all hulls are made to follow regular standards governed by a constant form of framing for the hull differing only in 35 the breadth and height of their members in accordance with the nature of the vessel concerned.

By the adoption of the invention also it is claimed that hulls of greater stability, 40 greater carrying capacity (length for length), better sea going qualities, and higher speed, are obtained than is possible under the present systems or methods of construction.

45 The invention therefore consists in constructing ships' hulls of frames formed by ribs extending outwards from each side of a keel frame in the ordinary manner, but all of which ribs are made of the same contour. 50 That is to say, each rib is made so as to incline outwards and upwards from the keel at a set angle, to form the ship's bottom, and then at its outer end to turn in a curve vertically upward to form the ship's side. 55 All of such ribs in the hull follow the same

angle of inclination of their bottom members so that they all, whether made of wood, or metal, may be cut or formed by machinery suitable for the purpose upon the same lines. The length of the ribs' bottom 60 and side members will vary from the bow to the stern so that the required longitudinal sweep of the sides from the bow to the stern may be provided for in the assembling of the ribs upon the keel. Likewise the 65 heights of the vertical members of the ribs will vary in order to obtain the sweep of the ship's bottom from bow to stern. In all ribs however, the angle of the bottoms to the sides is the same. This angle may, how- 70 ever, be varied at will in different ships according to the purpose for which the ship is to be employed, the angle of the bottom to the keel being made flatter as greater space and less speed is required. Also, the curve 75 of the rib to form the bilge, as it bends from the bottom member to the vertical may be varied to suit different requirements although all the ribs in each hull have a uniform curve.

80 The keel in such a construction may be made to extend upward as a bulkhead throughout the full height of the hull and for its full length, the upper ends of the ribs being joined thereto by the cross deck 85 beams extending horizontally between them.

A hull frame thus constructed may be covered by steel plates that may be riveted or welded together on to the ribs in any of the approved ways, or may be covered in 90 by wooden planking.

The method of construction involved herein is illustrated in the accompanying diagrammatic drawings of the frame of a hull it being understood that as the method 95 may be varied in its details to accord with different circumstances, the drawings can only be considered as illustrative thereof.

In such drawings:—

Figure 1 is a plan, and

Figure 2 a side elevation of the frame, showing also in dotted lines the contour of the hull when completed by the plating or planks employed.

Figure 3 is a half front elevation, and 105 half cross sectional elevation looking towards the stern of the frame.

The frame is constructed with a central keel plate A, which may extend right up the full depth of the hull to constitute a 110

longitudinal bulkhead dividing the hull into two independent halves in order to lessen risk of sinking through damage of any kind to the hull. To the keel plate the 5 transverse ribs B are fastened in any of the approved and known methods, these ribs being arranged at the required distances apart. These ribs, also, in this invention are made of uniform contour throughout 10 the full length of the ship, each rib being shaped with a bottom member C extending outward and upward at an inclined angle from the keel and then curving to the vertical to form the side member D. The angle 15 of inclination of all the ribs to the keel is the same and the radius of the curve as the ribs bend to the vertical is also the same. The relative lengths of these members are varied, the bottom members C decreasing 20 in length from amidships toward the stern and the bow in order to provide for the longitudinal sweep of the ship's beam, as indicated by the dotted lines in Figure 1. Likewise the vertical members vary in length, 25 decreasing as they extend from amidship to the stern but increasing in length as they extend from amidship to the bow, in order thus to obtain the desired shear and cut-water for the hull, as indicated in Figure 3 30 and by the dotted lines in Figure 2, the points of the ribs' attachment to the keel plate A varying to correspond.

Owing to the shape of vessels as heretofore constructed, the water is opened by 35 the bow when the vessel is sailing, starting a wave, but a different direction is given to the water a few feet from the bow, producing a second wave, while a few feet farther on, the water is twisted in still a different 40 direction, making a third wave, and so on, while much boiling and commotion of water is produced under the counter; all of these churning of the water using up power and retarding the vessel. One of the objects of 45 the invention is to avoid this loss of power, and to this end the water is caused to have an even flow, by starting the angle of the water cradle at the ship's fore foot, and preserving this angle for the entire submerged length of the vessel. The hull has 50 an upright stem, which terminates in a fore foot, and the water opens at the bow, and there is merely an increase in the extent of this opening to the point of greatest 55 beam, and then there is a gradual decrease of the opening until the water leaves the ship's stern. The floor of the ship is continuous and of uniform inclination from bow to stern. Moreover the bow portion 60 of the floor gives the ship an easy pitching motion, and has a tendency to lift the bow when the ship is in motion, because said bow portion of the floor slopes down at a slight angle toward the midship section.

65 At all speeds through the water the hull

will trim itself, and its shape will conform to the displacement of the water which is effected by the fore portion of the ship. Whatever angle the ship makes in going through the water at any speed, at all 70 speeds she will form that particular angle, to suit her hull. The hull has a sharp prow and is so shaped that the angle of entrance into the water is always substantially preserved until leaving the water. The floor is 75 the same angle from one end of the vessel to the other, so as to form a perfect sweep, without any doubles or twists in it for the water to follow. The water flows easily around it, without changing the shape of 80 the depression in the water, or twisting the water into other angles in its travel along the ship's side.

The rise of the hull from the middle fore and aft, or in other words the spring of 85 the hull, is to make the vessel easy in a head sea. The ship pitches easily and lightly. The angle from the keel to the bilge allows great beam without pounding in a head sea, besides giving speed. It also prevents drag 90 of dead water. The great width of bottom gives great stability, and the angle of the floor, that is, the line of inclination of the floor to the bilge, gives easy stability, an easy swing. The skin friction is largely 95 reduced, and the liability of rolling is also greatly reduced. The ship is easy in the sea, and does not pitch over and roll quickly on its beam ends and right back again. The ship will go over slowly, and pick itself up 100 slowly, and cushion itself.

It will be seen that a fast vessel with fine lines and a clean hull may be constructed with broad beam, and that my invention gives substantially greater carrying capacity 105 and substantially more stability for a given length. When the boat heels over, it has a tendency to creep to windward. To explain this feature, it will be noted that on each side of the bottom of the boat has a fair 110 amount of bed rise, that is, the angle from the keel to the bilge, and that the line of the bottom is substantially straight, the bottom forming one continuous plane from fore foot to counter, the plane being curved 115 from amidships to give the required rise toward bow and stern. The floor of the boat on the lee side is of ample breadth and length to stabilize or carry the boat when it is pressed over to either side, and the resistance to the boat's progress is much eased on the windward side, and consequently the power impelling the boat tends to turn it toward the side of less resistance, or in other words to turn the boat as on a pivot 120 or fulcrum located about at the point where the bow portion merges into the amidships portion, the direction of turning being to windward. This is also favored by the force 125 of the wind beating against the exposed 130

under portion of the vessel on the windward side, the vessel tending to shear toward the weather bow.

I claim:—

5. 1. In ships' hull, a hull frame having its transverse ribs each formed of a bottom portion and a side portion, the bottom portion of each rib extending outward and upward at an angle from the keel and then 10 curving to the vertical to form its side portion, the angle of inclination of all the ribs to the keel being the same and the radius of the curve as the ribs bend to the vertical being the same in all the ribs.
15. 2. A ship's hull having a stern terminating in a forefoot and having a sharp prow and formed to cause the water to have an even flow, by starting the angle of the water cradle at the forefoot, and substantially 20 preserving this angle for the entire submerged length of the vessel, the flow of the hull being continuous and of substantially uniform outward and upward inclination from bow to stern, the bow portion of the 25 floor sloping down at a slight angle toward the midship section, said floor having relatively great width, the bottom forming one continuous plane from forefoot to counter, the plane being curved from amidship to 30 give the required rise toward the stern, the sides of the hull extending below the water line from the foot substantially to the counter and forming the same angle with the bottom throughout substantially the 35 entire submerged portion of the hull.
3. A ship's hull formed so that the water opens at the bow, and so that there is merely an increase in the extent of this opening to the point of greatest beam, and then a 40 gradual decrease of the opening until the water leaves the stern, said hull having a stem terminating in a foot and having a

sharp prow and a floor extending substantially from the foot to the stern, said floor being continuous and having a substantially 45 uniform line of outward and upward inclination from the keel to the bilge and substantially from bow to stern, the bow portion of the floor sloping down at a slight angle toward the midship section, and the stern portion of the floor sloping slightly 50 upwardly, the hull curved upwardly from the floor at the bilge to form straight sides substantially throughout the submerged portion of the hull. 55

4. A ship's hull having a stem-terminating in a forefoot and having a sharp prow and also having a floor extending substantially from the forefoot to stern, the floor having a uniform outward and upward angle from 60 keel to bilge substantially throughout its length so as to form a substantially perfect sweep, the hull curving upwardly at the bilge to form straight sides, the angle of the floor with the sides being substantially 65 uniform throughout the submerged portion of the hull.

5. A ship's hull having a forefoot and also having a floor extending substantially from the forefoot to stern, the floor having 70 a uniform outward and upward angle from keel to bilge substantially throughout its length so as to form a substantially perfect sweep, the hull curving upwardly at the bilge to form straight sides, the angle of the floor with the sides being substantially 75 uniform throughout the submerged portion of the hull, the floor having a rise from the middle both fore and aft to make the vessel easy in a head sea. 80

Dated at Auckland this 11th day of October, 1918.

HENRY ANGUS NICHOLSON.
